UNITED STATES PATENT OFFICE

2,496,966

DRAWER PULL

Frank G. Szager, Inglewood, Calif.

Application September 5, 1945, Serial No. 614,560

2 Claims. (Cl. 16—115)

1

The present invention relates to certain novel and useful improvements in so-called drawer pulls, and the purpose of the invention is to structurally, functionally, and otherwise improve upon pulls now known to me.

There are, of course, many different types of handles, knobs, and grips used for drawer pulls. The present invention relates to a type in which the main body part is in the form of a receptacle, this sunken and mounted in the face of the drawer, and being provided with a projectible and retractable grip constituting the pull proper.

More specifically, novelty is predicated upon a receptacle forming a receiving and protective well for the projectible and retractable pull or gripping means. The latter is of special construction and is hingedly mounted between its ends with means at one end providing finger-grips, and means at the opposite ends forming a conveniently accessible actuator for said finger-grips.

Other objects, features and advantages will become more readily apparent from the following description of the accompanying illustrative drawings.

In the drawings, wherein like numerals are employed to designate like parts throughout the views:

Figure 1 is a front elevation of a conventional drawer equipped with a so-called pull constructed in accordance with the principles of the present invention.

Figure 2 is an enlarged fragmentary detail view, partly in section and partly in elevation, this taken on the plane of the line 2—2 of Figure 1, looking in the direction of the arrows, and showing the pull in its projected or extended position in readiness for use.

Figure 3 is a top plan view with a portion broken away and shown in section to show the method of fastening.

Figure 4 is an enlarged detail view of the pull unit by itself.

As will be hereinafter seen novelty is thought to reside in the combination of the open front elongated receptacle with a hinge pin across its front serving as a mount for the knuckle-equipped portion of the retractable and projectable pull. Then, too, novelty is predicated upon the pull unit per se depicted in Fig. 4 of the drawings and hereinafter specifically described.

In the drawings the reference character A designates a frame to accommodate the drawer B, the latter being equipped with the improved pull.

As before indicated the invention comprises an attaching device 5 characterized by an elongated

receptacle 6 having a marginal facing flange 7. This provides the aforementioned well or receptacle and it is secured in place by wood screws 8. The gripping unit or pull is denoted by the numeral 9. This as shown in Figure 4 is formed from a single piece of metal which is bent intermediate its ends to define a pair of duplicate diverging limbs or finger-grips 10. These are provided adjacent their outer ends with indentations 11 to facilitate surety of grip and convenience of operation. The intermediate portion of the unit is fashioned into a tubular attaching hinge or knuckle 12 and the remaining portion 13 is formed into a flattened actuator. A hinge 15 and attaching pin 14 serves to secure the unit 9 swingably in the well in the manner shown. It follows that the entire unit 9 can be swung flush into the well of the receptacle 5 in which position it is completely out-of-the-way. When it is desired to bring it into use pressure is brought to bear on the actuator 13 which swings the finger-grip 10 out. Then, the finger-grips are grasped in obvious manner by placing the fingers in the anti-slipping indentations 11.

25 The device is of utmost simplicity and is compact and convenient, takes up little or no space, especially in places where space is limited and needed. In spite of its simplicity it provides an adequate pull affording the user a firm and reliable grip. It lends itself adaptable for use in drawers and tool boxes and elsewhere where space is at a premium.

30 Changes in shape, size, materials and rearrangement of details and parts may be resorted to in actual practice, so long as they do not depart from the spirit of the invention or the scope of the appending claims, as is well understood.

I claim:

1. A drawer pull of the class shown and described comprising a shallow elongated receptacle closed at its back and open at its front, a hinge pin transversely bridging said open front and spaced a predetermined distance from said back and also located centrally with respect to the opposite transverse end portions of said receptacle, a drawer pull provided adjacent one end portion with a knuckle, the latter hingedly mounted on said pin, said one end portion, on one side of said knuckle, constituting a finger-trippable actuator and the length of the latter being less than the depth of said receptacle, the opposite end portion of said pull embodying limbs projecting from the other side of said knuckle, said limbs being of lengths equal to each other but less than the distances between the hinge

pin and transverse ends of said receptacle in order to fold without hindrance into said receptacle on either side of said pin, and said limbs being provided with depressions constituting finger-holds.

2. As a new article of manufacture, a stamped sheet material drawer pull comprising a pair of duplicate limbs disposed alongside one another and integrally connected to each other at corresponding ends and provided with outstanding semi-circular bends, the latter being opposite one another and aligned to combinedly define a cylindrical hinge knuckle, the end portions between said connected ends and knuckle being in contact and forming a finger-trippable actuator on one side of said knuckle, the portions of said limbs, on the other side of said knuckle, being spread into spaced divergent relationship, having their ends disconnected and portions, inwardly of the

disconnected ends, provided with concavo-convex indentations, the convex portions of which are in contact, said indentations defining finger-holds.

FRANK G. SZAGER.
